UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

TELEPHONE CIRCUITS AND METHOD OF OPERATING THE SAME.

Application filed September 5, 1919. Serial No. 321,890.

To all whom it may concern:

Be it known that I, KENNETH S. JOHNSON, a citizen of the United States, residing at Jersey City, in the county of Hudson, State of New Jersey, have invented certain new and useful Improvements in Telephone Circuits and Methods of Operating the Same, of which the following is a full, clear, concise, and exact description.

10 This invention relates to telephone circuits and more particularly to circuits having a branch through which it is desirable at times to prevent the passage of talking currents, as for example, to render a substation circuit

15 anti-side-tone.

It is the object of the invention to provide a method and means for preventing the passage of talking currents through one branch of a circuit of the above type, when 20 the portion of the circuit adjacent said branch is employed for transmitting currents to another portion of the circuit, but permitting the passage of currents through said branch when such currents are received 25 from another source of currents.

In the embodiment of the invention disclosed herein, a two-button transmitter is employed in a circuit having three branches, i. e., a circuit comprising three electric paths 30 between two common terminals. One of these branches comprises a telephone line, one comprises a receiver, and one comprises a balancing impedance which in two of the forms of the invention shown is partially or 35 wholly incorporated in one button of said transmitter. The relation of impedances and the direction of electromotive forces generated in the transmitter buttons are such that, on transmitting, substantially no talking current flows through the receiver.

40 While the invention is shown applied to substation circuits, it is obvious that it is applicable to other circuits where it is desired to transmit variable currents without 45 actuating an electrical device in one branch of the circuit.

Furthermore, it is obvious that other types of transmitters, such as the electromagnetic or electrostatic types, may be employed instead of the carbon button type. In 50 the appended claims, the expression "two-

element transmitter" is intended to mean a transmitter having two elements, each of which is capable of generating a variable electromotive force in response to mechanical vibrations.

The invention will be more fully understood from the following detailed description and claims taken in connection with the accompanying drawings, in which Fig. 1 is 55 a diagrammatic view of one form of the invention; Fig. 2 is a similar view showing the direction of currents in Fig. 1, when transmitting, and showing the balancing impedance as separate from the transmitter; 60 Fig. 3 represents another form of the invention; Fig. 4 shows the direction of currents in Fig. 3 when transmitting; Fig. 5 represents a third form of the invention; Fig. 6 shows the direction 65 of currents in Fig. 5, when transmitting and shows the balancing impedance as separate from the transmitter; Fig. 7 represents diagrammatically a transmitter which may be used in the circuits of Fig. 1 or of 70 Fig. 5; and Fig. 8 is a similar view of a transmitter which may be used in the circuit of Fig. 3.

In Figs. 2, 4 and 6 the portions of the circuit through which current variations do 75 not flow are shown in dotted lines.

Referring to Fig. 1, the circuit may be considered to consist of three branches 10, 11 and 12. The branch 10 comprises the line L and one button T_2 of a two button 80 transmitter. The branch 11 comprises the receiver R and the branch 12 comprises the other transmitter button T_1 . The button T_1 is preferably designed to have an impedance 85 which will properly balance the impedance of the line and render the substation anti-side tone. Additional impedance may, however, be inserted in series in branch 12 as indicated at X in Fig. 2. The source of 90 direct current is not shown, since it will ordinarily be located at a central station.

The condenser C may be employed to confine the direct current to the branches containing the transmitter buttons. Obviously, the transmitter may be energized by a local 95 source of current if desired.

The transmitter buttons are so arranged

that on transmitting, the electromotive forces generated therein aid each other in the series circuit comprising branches 10 and 12. The values of these electromotive forces are such that equal potential variations occur at the receiver terminals and substantially no variable current flows through the receiver. Assuming that the electromotive force in a transmitter button is proportional to the square root of its impedance, the following impedance relations must exist for no side tone:

$$T_1 = T_2 + 2L + \frac{L^2}{T_2} \quad (1)$$

15

In equation (1) T_1 , and T_2 and L represent the impedances respectively of the elements above designated by these characters. This formula is derived as follows:

20 Let the electromotive force generated in the button T_1 be represented by $K\sqrt{T_1}$ and the electromotive force in T_2 by $K\sqrt{T_2}$. Since it is assumed that there is no current in R , the current flows serially through the 25 line and the two transmitter buttons. Designating this current by I , then by Ohm's law

$$30 \quad I = \frac{K\sqrt{T_1} + K\sqrt{T_2}}{T_1 + T_2 + L} \quad (2)$$

Since the alternating current potentials at the terminals of R must be equal, the electromotive force generated by T_1 must be equal to the potential drop therethrough produced by the current I . Hence,

$$K\sqrt{T_1} = IT_1 \quad (3)$$

Substituting the value of I from equation 40 (2) in equation (3), we get:

$$K\sqrt{T_1} = \frac{KT_1(\sqrt{T_1} + \sqrt{T_2})}{T_1 + T_2 + L} \quad (4)$$

45 Solving this equation for the value of T_1 , we obtain equation (1) given above.

If the transmitter buttons in the circuit of Fig. 1 are in conductive relation to the diaphragm, the transmitter may be of the type shown schematically in Fig. 7, wherein 50 the two buttons are arranged to be compressed simultaneously by the diaphragm. The push-pull transmitter shown in Fig. 8 may be used if the direct current is made to flow through the buttons in parallel.

55 In Figs. 3 and 4 the receiver is placed in the branch 12 and the balancing impedance X in the branch 11. To insure no side tone in this form the electromotive forces generated in the transmitter buttons must be 60 opposed and the change in electromotive force in button T_1 must be equal to the change in potential drop through impedance X .

65 The circuit of Figs. 5 and 6 is similar to that of Fig. 3, except that the balancing im-

pedance and the line are interchanged and the change in electromotive force in button T_1 must be equal to the change in potential drop through the line. As shown in Fig. 5, the balancing impedance may be wholly included in transmitter button T_2 .

The form of transmitter represented in Fig. 8 may be used in Figs. 3 and 4. The arrangement is such that one button is compressed when the other is expanded, thus 75 producing opposite potential variations when the direct current is flowing through the buttons in series. In Figs. 5 and 6, when current supplied by a central battery flows through the buttons in parallel, the 80 transmitter of Fig. 7 may be used.

What is claimed is:

1. A circuit comprising three branches, a device for converting sound waves into electric waves in each of two of said branches, and means for simultaneously actuating said devices, the electromotive forces generated by said actuation being so proportioned that substantially no current variations will flow in one of said branches, a receiver in said last mentioned branch and a line circuit included in one of the others of said branches.

2. A circuit comprising three branches, a receiver in one of said branches, a device 95 for converting sound waves into electric waves in each of two of said branches, and means for simultaneously actuating said devices, the electromotive forces generated by said actuation being so proportioned that 100 substantially no current variations will flow in said receiver.

3. A circuit comprising three branches, a device for converting sound waves into electric waves in each of two of said branches, 105 a receiver in the third of said branches, and means for simultaneously actuating said devices, the electromotive forces generated by said actuation being so proportioned that 110 substantially no current variations will flow in said receiver.

4. The method of operating a three-branched telephone circuit, which comprises converting sound waves into alternating electromotive forces in each of two of said 115 branches of such values that substantially no current flows in one of said branches.

5. The method of operating a three-branched telephone circuit, which comprises converting sound waves into alternating electromotive forces in each of two of said 120 branches of such values that substantially no current flows in the third of said branches.

6. A telephone circuit comprising a line, and two branches connected to said line, a two-element transmitter having one element in said line and one element in one of said branches, and a receiver in one of said branches, the impedances of said elements being so proportioned to each other and to 125 130

the impedances of the line and of the branch not containing the receiver that said receiver is substantially anti-side tone.

7. A telephone circuit comprising a line, 5 and two branches connected to said line, a two-element transmitter having one element in said line and one element in one of said branches, and a receiver in the other of said branches, the impedance of said elements 10 being so proportioned to each other and to the line impedances of the line and of the first of said branches that said receiver is substantially anti-side-tone.

8. In combination, a line, a two-element 15 transmitter connected to said line, a receiver in a branch in shunt to one of said elements, and means for actuating said elements to produce talking currents in series therethrough, the impedance of said shunted element being so proportioned to the imped- 20 ances of the other element and of the line that the terminals of said receiver are subjected to substantially the same potential variations during said actuation.

25 9. In combination, a line, a transmitter

comprising a diaphragm and two buttons in contact with one face thereof, opposite sides of said line being connected to said buttons respectively, and a receiver having one terminal connected to said diaphragm and one 30 terminal connected to said line.

10. In a telephone circuit, two devices for converting sound waves into electric waves, and a receiver so connected thereto that when said devices are simultaneously actuated 35 by a sound wave substantially no current will flow in said receiver.

11. In a telephone circuit, two devices for converting sound waves into electric waves, and a receiver connected thereto, said de- 40 vices being so designed that when actuated by a sound wave they will generate electro- motive forces so related to the impedances of the respective circuits of said devices that said electromotive forces substantially balance each other in said receiver.

In witness whereof, I hereunto subscribe my name this 2nd day of September A. D., 1919.

KENNETH S. JOHNSON.
